UNITED STATES PATENT OFFICE.

DAVID E. GRAY, OF WHITE PLAINS, NEW YORK.

SHUTTLE AND PICKER-STICK CHECK.

1,062,395.

Specification of Letters Patent.

Patented May 20, 1913.

Application filed June 28, 1908. Serial No. 440,518.

To all whom it may concern:

Be it known that I, DAVID E. GRAY, a citizen of the United States, residing at White Plains, in the county of Westchester and State of New York, have invented certain new and useful Improvements in Shuttle and Picker-Stick Checks, of which the following is a specification.

My invention relates to a checking device for the shuttle and picker stick.

Heretofore it has been common to stop or check the picker stick in its forward movement by a bumper more or less yielding in character and to check it in its backward movement either by friction applied directly to the stick or by a long strap connecting the opposite shuttle boxes and passing around the two sticks. Such devices or their use consume or necessitate a great deal of power, cause wear and tear on the parts of the machine and make a great deal of noise.

It is my object to reduce the power required to operate, to avoid noise, vibration and wear and tear and to provide a device which is inexpensive and yet efficient and durable. Incidentally it will be found to be compact and adapted to a great variety of types of looms.

Briefly described it comprises in its simplest and most complete form, a movable checking loop in which the picker stick oscillates. Guides are provided for the loop some of which are adjustable to afford the proper resistance to the movement of the loop.

The accompanying single sheet of drawings illustrates one form of the invention but it will be understood that I do not consider the invention as limited or specific in its scope any more than will be hereinafter set forth in the claims.

Figure 1 is a side view of parts of a loom illustrating my invention, the picker stick and shuttle being shown in full lines in their backward position and in dotted lines in the forward position. Fig. 2 is a bottom view of the parts in the full line position of Fig. 1. Fig. 3 is an end view and a partial vertical section on the plane of the line X-X. Fig. 1 looking in the direction of the arrows.

The picker stick 1 is operated in any suitable manner and the picker 2 operates the shuttle 3 as usual. The support 4 which in the ordinary loom is one end of the lay

carries the shuttle box 5. The usual binder 6 may be used if desired.

On opposite sides of the support 4 are secured frames 7 and 8 having hook-like guide fingers 9, 10, 11 and 12. The checking device 13 is in the form of a strap which passes around the picker stick and the fingers 9, 10, 11 and 12. The lateral guides 14 and 15 are adjustable in and out relative to the end guides so as to make it possible to increase or diminish the friction of the checking loop. For this purpose the flange 16 of each frame is slotted and the base of the corresponding lateral guide is secured to it by a bolt 17.

When the picker stick is thrown forward from the position shown in full lines in Fig. 1 it engages the front bight 18 of the loop and pulls the loop forward with it. The friction of the loop on the guides retards the loop and thus brings the stick to rest without excessive shock in the position shown dotted in Fig. 1. The action is just the reverse on the backward stroke of the picker stick. The friction of the loop on the guides is sufficient in fact to stop the picker stick before it reaches the rear end of its stroke. This leaves the picker in a position just above the rear guides 9 and 11. The shuttle on its return hits the picker and drives the stick backward to the full line position of Fig. 1. The loop thus indirectly checks the shuttle. It is therefore not necessary to adjust the binder 6 as tight as it ordinarily is. Less power is therefore required to throw the shuttle forward as there is less friction of the binder.

To facilitate assembling the attachment on the loom I prefer to secure the frame 7 and 8 to the support 4 by screws or bolts such as 19 and 20 which pass through slots in the sides of the frames. This permits the frames to be adjusted properly after the bolts have been placed in an approximately correct position.

By the term picker stick I mean to include all devices of whatever shape or mode of operation which serve to throw the shuttle out of its box.

The yielding character of the check prevents the severe shock formerly encountered on the forward stroke of the picker stick. There is thus less breakage of sticks with my attachment. The stick is also saved

from strain on the return stroke. The picker being movable when the shuttle strikes it is also less subject to wear.

What I claim is:

- 5 1. A checking device for a loom comprising two pairs of end guides spaced apart laterally, a checking strap passing around said guides and lateral guides outside of the checking strap and between the end guides,
- 10 10. one or more of said guides being laterally adjustable relative to the others for varying the effective length of the strap.
- 15 2. A checking device for a loom comprising two pairs of end guides spaced apart laterally, a checking strap passing around said guides and lateral guides outside of the checking strap and between the end guides, said lateral guides being adjustable toward and from each other.
- 20 3. A checking device for a loom comprising a strap, two pairs of end guides therefor, a guide between the guides of each pair of end guides and adjustable with relation thereto for varying the effective length of
- 25 4. A checking device for a loom comprising, a traveling checking strap in the form of a loop, guides therefor, one or more of said guides being adjustable with relation to the others for varying the effective length of the strap.
- 30 5. A checking device for a loom comprising, a traveling checking strap in the form of a loop, guides therefor, two of said guides being adjustable with relation to the others for varying the effective length of the strap.
- 35 6. In a checking device for a loom, a pair of side plates having depending guide fingers with outwardly flaring shoulders, a
- 40 7. In a checking device for a loom, a lay, guide fingers carried thereby and adjustable along the length thereof, a traveling checking strap supported thereon and lateral guides adjustable relative to said supporting guide fingers for varying the effective length of the strap.
- 45 8. In a checking device for a loom, two pairs of guide fingers, a traveling checking loop around said guide fingers and a pair of guide fingers arranged outside of said loop and against which said loop is drawn when in operation, some of said guide fingers having laterally flaring flanges for supporting said loop.
- 50 9. In a checking device for a loom, a plurality of interior guide fingers, a traveling checking loop surrounding said guide fingers, a pair of external guide members co-acting with the outer surface of said loop and laterally slotted supports for said guide members whereby said guide members may be laterally adjusted.
- 55 10. In a checking device for a loom, a plurality of interior guide fingers, a traveling checking loop surrounding said guide fingers, an external checking member frictionally engaging the outer surface of the loop at a point between the two of the interior guide fingers at one side of the loop and means for supporting the loop in proper engagement with the guide fingers.

traveling checking strap supported thereon, and lateral guides within the line of said guide fingers for holding the strap on said fingers.

7. In a checking device for a loom, a lay, guide fingers carried thereby and adjustable along the length thereof, a traveling checking strap supported thereon and lateral guides adjustable relative to said supporting guide fingers for varying the effective length of the strap.

8. In a checking device for a loom, two pairs of guide fingers, a traveling checking loop around said guide fingers and a pair of guide fingers arranged outside of said loop and against which said loop is drawn when in operation, some of said guide fingers having laterally flaring flanges for supporting said loop.

9. In a checking device for a loom, a plurality of interior guide fingers, a traveling checking loop surrounding said guide fingers, a pair of external guide members co-acting with the outer surface of said loop and laterally slotted supports for said guide members whereby said guide members may be laterally adjusted.

10. In a checking device for a loom, a plurality of interior guide fingers, a traveling checking loop surrounding said guide fingers, an external checking member frictionally engaging the outer surface of the loop at a point between the two of the interior guide fingers at one side of the loop and means for supporting the loop in proper engagement with the guide fingers.
